UNITED STATES PATENT OFFICE.

JOHN C. THOMPSON, OF CINCINNATI, OHIO.

GEARING.

1,074,579.

Specification of Letters Patent. Patented Sept. 30, 1913.

Application filed March 29, 1910. Serial No. 552,261.

To all whom it may concern:

Be it known that I, JOHN C. THOMPSON, a citizen of the United States, residing at Cincinnati, in the county of Hamilton and State of Ohio, have invented a certain new and useful Gearing, of which the following is a specification.

The object of my invention is to provide a gearing device of this class of simple, durable and inexpensive construction and also to provide improved means, whereby the means for driving the agitator shaft of the washing machine may be automatically thrown out of gear when the washing machine cover is raised and also to provide a device of this class in which the speed of rotation of the driving motor may be greatly reduced as applied to the agitator shaft with a minimum of gearing device to thereby provide a gearing device of few parts not liable to get out of gear.

My invention consists in certain details, in the construction, arrangement and combination of the various parts of the device, whereby the objects contemplated are attained, as hereinafter more fully set forth, pointed out in my claims and illustrated in the accompanying drawings, in which:

Figure 1 shows a vertical, central, sectional view of a washing machine having a gearing device embodying my invention applied thereto. Fig. 2 shows a top or plan view of same. Fig. 3 shows a diagram illustrating the gearing device for the agitator shaft. Fig. 4 shows a detail, plan view of the belt guide and supporting device, and Fig. 5 shows a detail, sectional view of a wringer embodying my invention illustrating the device for preventing clothes from winding on the rollers and also the device for use in feeding clothes to the rollers.

Referring to the accompanying drawings, I have used the reference numeral 10 to indicate that portion of the washing machine shown having on one side a wringer support 11 to which a wringer 12 of the ordinary kind is applied. On top of the washing machine is a hinged cover 13 provided with the hinges 14 and arranged to swing open 50 in a direction away from the wringer. Beneath the washing machine body is a platform 15 on which a motor 16 is supported provided with a small pulley 17 on its shaft. The agitator shaft is indicated by the number 18 and fixed to the upper end thereof is a gearing device consisting of a central

hub 19 having a series of radial arms 20 thereon, which radial arms support the body portion of the gearing device which is indicated by the numeral 21 and which is segmental in shape when viewed from the top and comprises slightly more than a half circle. On the outer face of the body portion 21, I have provided a continuous row of gear teeth 22 and in the central portion thereof, I have provided a straight guide rib 23 as shown in Fig. 3. Mounted on the hinged cover 13, near one side thereof, is a bearing 24 in which is supported a shaft 25. This shaft is held against outward movement by means of a collar 26 keyed thereto and on the outer end of said shaft is a clutch member 27 slidably and non-rotatably supported by means of the key 28. At the inner end of the shaft 25 is a universal joint 29 and a shaft 30 is connected with said universal joint and is provided with a pinion 31 and a roller 32 on the pinion. To support this shaft 30 I have provided a device 33 having an oval opening 34 therein and rotatably mounted upon the shaft is a bearing 35 held against longitudinal movement of the collars 36 and 37 so that said bearing 35 rests within the oval opening 34. The parts are so arranged and proportioned 85 that the roller 32 will hold the pinion 31 in engagement with the gear teeth 22 and as the shaft 30 is rotated the said pinion 31 will traverse the gear teeth of the body portion 21 and impart an alternating rotary motion 90 to the agitator shaft 18. The parts are also so proportioned that the pinion 31 may make a number of revolutions, preferably three, in order to traverse the gear teeth 22 one complete revolution so that the speed 95 between the shaft 25 and the shaft 18 is reduced into a proportion of about three to one.

In order to apply power from the motor to the shaft 25, I have provided the following mechanism: Mounted upon the side of the washing machine body 10 is a bracket 38 having a shaft 39 rotatably mounted at its upper end and provided with a clutch device 40 to coact with the clutch device 27. 105 The shaft 39 also is provided with a sprocket wheel 41 and a large belt wheel 42. A belt 43 connects the belt wheel 42 with the pulley 17 and the end of the shaft 39 stands spaced apart from the end of the shaft 25. 110 However when the clutch member 27 is moved on the shaft 25 the said shaft will be

connected to rotate in unison but when the clutch member 27 is withdrawn, as shown in Fig. 1, the shaft 25 and the cover of the washing machine may be elevated without 5 moving the shaft 39.

For operating the wringer I have provided the following mechanism: Rotatably mounted on the wringer shaft is a hub 44 having a sprocket wheel 45 thereon connected by a sprocket chain 46 with the sprocket wheel 41 and slidably mounted upon the wringer shaft is a clutch member 47 controlled by a rod 48 which rod is connected to a lever 49 fulcrumed to the 10 wringer. When the clutch member 47 is in the position shown in Fig. 2, the wringer shaft will be rotated and when it is moved to its opposite limit the wringer shaft will remain inoperative.

20 In order to provide for throwing the agitator shaft out of gear when the cover is raised I have provided the following mechanism: Slidably mounted upon the cover 13 is a bar 50 having one end extended upwardly into engagement with the sliding clutch member 27. At the other end of the bar is a handle 51. Fulcrumed to the cover 13 is a bell crank lever 52 pivoted to the bar 50, and also pivoted to a slide bolt 53 which 25 bolt is designed to coact with a keeper 54 secured to a stationary part of the machine cover. By this arrangement it is obvious that when the parts are in the position shown in Fig. 2, the slide bolt will be disengaged from its keeper and the clutch member 27 will be disengaged from its mating clutch member; then when the handle 51 is operated to move the clutch members into engagement with each other, the bell crank 30 lever will also be operated to move the slide bolt 53 in engagement with its keeper so that by this arrangement the double function is accomplished by latching the cover when the agitator shaft is in gear and of 35 unlatching the cover when the agitator shaft is thrown out of gear. Obviously before the cover may be raised, the latch must be released and when this is done the agitator shaft is thrown out of gear and 40 when the cover is closed it must be latched before the gearing device can be thrown into operation. One of the important results that are gained by the use of my improved gearing device is that few working 45 parts are employed, there being only one pinion which is in mesh with the gearing device on the agitator shaft. However, by making the gearing device on the agitator shaft of such size that the pinion 31 must 50 make a number of revolutions to each revolution of the agitator shaft, I avoid the necessity of providing additional speed reducing gearing devices. Furthermore by 55 providing the main power shaft 39 connected directly to sprocket gearing with the

wringer shaft, I provide a very simple gearing for the wringer and also provide means whereby the wringer may be thrown into or out of gear very quickly and easily. I have also provided a belt guide arranged to hold the belt in position either when crossed or uncrossed as follows: The numeral 55 indicates an oval metal loop having an opening at one side through which a belt may be admitted and also provided with flanges 56 at its ends whereby it may be secured to the sides of the washing machine body. It is preferably arranged at that point upon the body where the belt would be crossed when used in this manner and obviously when removing and replacing the belt to cross it or to uncross it, said guide will hold the belt in position so that it need not be removed from both pulleys.

60 In use the motor is permitted to operate the shaft 36 during the entire operation of washing and wringing and the operator, by manipulating the handle 51 and the cover 49 may throw either the wringer or the washing machine into or out of gear very 65 readily and easily or both may be thrown into gear at the same time. In the event that it is desired to reverse the movement of the wringer this may be accomplished 70 very quickly and easily by removing the belt from the pulley 17 and then crossing it or it may be accomplished by reversing the movement of the motor. The guide device for the belt performs an important function in holding the belt in position in case 75 it is removed from the pulley 17 to be crossed.

80 My improved device for preventing clothes from winding on the rollers of the wringer comprises a metal plate 55 connected at its upper edge to the sides of the wringer frame and extended across the wringer frame adjacent to the upper roller and arranged on the side of the wringer frame opposite from the side on which the 85 clothes are inserted. The lower edge of the plate is extended to a position close to the roller at a point a short distance from the point where the two rollers contact with each other as clearly shown in Fig. 5. I 90 have provided for making the plate adjustable toward and from the roller at its lower edge by means of a set screw 56 extended from the plate and seated in the wringer frame. I have also provided improved 95 means for feeding clothes to the wringer so that the operator's fingers will not become caught therein by providing a feeder board 100 57 arranged in a substantially horizontal 105 position adjacent to the side of the wringer in which the clothes are inserted. One edge thereof is arranged close to and 110 slightly below the level of the top of the lower roller so that the operator may, conveniently and easily, place clothes on the 115 120 125 130

feeder board and then by pushing them toward the rollers they will slide over the feeder board and enter between the rollers without the necessity of having the operator place his fingers in position adjacent to the rollers where they will likely become caught therein and in a device of this kind it is of especial value in connection with power operated wringers. In connection with the device for preventing clothes from becoming wrapped on the rollers of the wringer, I have found that the clothes in most instances wrap around the upper roller and I have therefore provided a scraper for the upper roller only arranged to loosen clothes from the upper roller and compelling them to pass outwardly beyond the rollers. Obviously, if desired, a similar scraper may be applied to the lower roller.

20 I claim as my invention:

1. A gearing device of the class described, comprising a support, a hinged member on the support, an upright shaft in the hinged member, a power shaft mounted on the side 25 of the support and having a clutch member thereon, a shaft mounted upon the hinged member in line with the power shaft and having a clutch member thereon to coact with the clutch member on the power shaft, means interposed between the shaft on the hinged member and the upright shaft on the hinged member for imparting an alternating 30 rotary motion to the latter by a continuous rotary motion of the former, and means for connecting and disconnecting said clutch device.

2. A gearing device of the class described, comprising a support, a hinged member on the support, an upright shaft in the hinged member, a power shaft mounted on the side 40 of the support and having a clutch member thereon, a shaft mounted upon the hinged member in line with the power shaft and having a clutch member thereon to coact 45 with the clutch member on the power shaft, means interposed between the shaft on the hinged member and the upright shaft on the hinged member for imparting an alternating rotary motion to the latter by a continuous rotary motion of the former, a latch device for the hinged member and a bar connected with the latch device and the clutch device for disconnecting them in unison when moved to one position and for closing 50 the latch device and connecting the clutch members in unison when in another position.

3. In a device of the class described, the combination of a support, a hinged member on the top of the support, an upright shaft 55 in the hinged member, a horizontally arranged shaft at the side of the support, a clutch member thereon, means for rotating said shaft, a second horizontally arranged shaft on said hinged member in line with the first, a sliding clutch member thereon to

coact with the clutch member on the first shaft, means interposed between the horizontally arranged shaft and the vertically arranged shaft on the hinged member for imparting an alternating rotary motion to the vertically arranged shaft by means of a continuous rotary motion applied to the horizontal shaft, said clutch members being arranged at one side of said hinged member so that when the hinged member is raised 70 the horizontally arranged shaft on the hinged member will move away from the shaft on the support, a slide bolt on the hinged member, a keeper for the slide bolt on the support adjacent to the slide bolt, a bell crank lever connected with the slide bolt, a bar slidably supported on the hinged member and having one end connected with the sliding clutch member, said bar also being pivoted to said bell crank lever, for the 75 purposes stated.

4. In a device of the class described, the combination of a support, a hinged member on the top of the support, a horizontally arranged power shaft at the side of the support 80 extended in a direction toward the center of the support, a horizontally arranged shaft on the hinged member in line with the shaft on the support, coacting clutch devices on said shafts, means for connecting and disconnecting them, a vertically arranged shaft on the hinged member, and means interposed between it and the horizontal shaft 85 for imparting an alternating rotary motion to the vertical shaft by a continuous rotary motion of the horizontal shaft, said clutch devices being arranged at one side of the hinged member, whereby the shaft on the hinged member will move away from the shaft on the support when the hinged member is elevated.

5. In a gearing device of the class described, the combination of a support, a hinged member for the support, a power shaft mounted on the support, an upright 100 shaft mounted in the hinged portion of the support, a horizontal shaft mounted on the hinged member of the support, means interposed between the two shafts on the hinged member of the support for imparting an alternating rotary motion to the upright shaft by a continuous rotary motion applied to the horizontal shaft, and means for operatively connecting or disconnecting the horizontal shaft on the hinged member of the support 105 from the power shaft on the support.

6. In a gearing device of the class described, the combination of a support, a hinged member for the support, a power shaft mounted on the support, an upright 110 shaft mounted in the hinged portion of the support, a horizontal shaft mounted on the hinged member of the support, means interposed between the two shafts on the hinged member of the support for imparting an 115

alternating rotary motion to the upright shaft by a continuous rotary motion applied to the horizontal shaft, and means for operatively connecting or disconnecting the 5 horizontal shaft on the hinged member of the support from the power shaft on the support, said means comprising coacting clutch members on said shafts and means

carried by the hinged member of the support for actuating said clutch.
